FIG. 1.

Inventor
Thomas R. Stoltenberg
James R. Offield, Atty.

UNITED STATES PATENT OFFICE.

THOMAS R. STOLTENBERG, OF MOLINE, ILLINOIS, ASSIGNOR TO MOLINE HEAT, OF MOLINE, ILLINOIS, A CORPORATION OF ILLINOIS.

DRAFT-REGULATING MECHANISM.

1,292,132.

Specification of Letters Patent.

Patented Jan. 21, 1919.

Application filed June 12, 1918. Serial No. 239,519.

To all whom it may concern:

Be it known that I, THOMAS R. STOLTENBERG, a citizen of the United States, and a resident of Moline, in the county of Rock Island and State of Illinois, have invented certain new and useful Improvements in Draft-Regulating Mechanism, of which the following is a specification.

My invention relates to draft regulating mechanism for regulating and controlling the draft intensity through heating devices such as furnaces, stoves or the like.

My improved apparatus may be applied to the heating device itself or to the smoke stack or the chimney and is automatically operated by air pressure caused by the chimney draft.

One of the important objects of the invention is to provide a free wide opening for the air regardless of the velocity, the arrangement of the opening being such that the inflow of air will be at an angle that is nearly in line with the travel of the air through the pipe or chimney, crowding of the air being thus prevented and the draft regulation made more efficient and the control more sensitive than in prior devices in which there is more or less crowding of the air at one side of the inlet aperture.

Another object of the invention is to provide improved mechanism for balancing the regulating door and for resisting and adjusting its response to the pressure of inflowing air.

The various features of my invention are clearly illustrated on the accompanying drawing in which—

Figure 1 is a front elevational view showing my improved apparatus applied to a chimney, and

Fig. 2 is a side elevational view with the chimney and rear part of the regulating device housing in vertical cross-section.

The housing 5 of the regulator attachment is in the form of a conical hood applied to the opening 6 in the chimney 7. In the lower wall 8 of the hood is the rectangular opening 9 whose angle with reference to the chimney opening 6 is such that the air can freely flow into and up through the chimney without crowding against the upper part of the housing. In prior structures the air is forced to enter the chimney flue at right angles thereto and the air will crowd toward the top wall of the chimney opening in proportion to the velocity but in my arrangement where the air enters in a direction nearly in line with the travel of air up the flue the flow is uniform regardless of the velocity, and there is no crowding.

Extending transversely through the housing near its apex and journaled in the side walls thereof is a shaft 10 on which the door 11 is secured at its upper end to swing within the housing from its lower closed position against the lower wall and to open position against the upper wall. On this shaft is mounted a pulley member 12 from which extends a stem 13 threaded at its outer end to adjustably receive a counterweight 14, the adjustment being such that the weight will balance the weight of the door 11. The pulley member can be detachably secured in any desired manner to the shaft, and the stem 13 may thread into the pulley and serve as a set screw for securing it to the shaft. The pulley member shown is semi-circular and has grooves 15 of different radii. A chain 16 which may be anchored at one end to the stem 13 engages in one of these grooves and at its lower end supports a weight 17, this weight tending to rotate the pulley and shaft and to swing the door downwardly and hold it closed against the pressure of air on its outer side. As the pressure component, that is, the total pressure of the air against the door, varies as the door assumes different angles in swinging upwardly, the weight tending to close the door should decrease proportionately in order that resistance to the air flow and regulation of the draft intensity through the furnace should be uniform and constant. The pulley member is therefore mounted eccentrically on the door shaft in order that when the door is swung upwardly and the pulley turned, the leverage distance between the chain 16 and the vertical plane of the shaft will decrease. The degree of eccentricity is such that a constant resistance will be offered against upward swing of the door throughout its range of movement. The door will thus respond nicely and efficiently to draft pressure and the furnace draft will be correspondingly regulated. For different furnaces or for different conditions the regulating door must be set to respond under greater or less resistance but such resistance

110

can be readily adjusted for by applying the chain 16 in that groove 15 which gives the desired leverage distance.

The cam member 12 can be attached to either end of the shaft 10. Under some conditions it may be desirable to reverse the cam member and for this purpose a hole 18 is provided at the other side of the center of the cam member for receiving the shaft 10. 10 This will enable application of the door controlling mechanism in such manner as will make it more accessible, for example, where the chimney adjoins a wall or where the regulator is placed in a corner.

15 In order that the door may be operated independently of its automatic controlling mechanism, a chain 19 is secured to the cam member and may extend to any location from which it is desired to manually or 20 mechanically control the regulator.

I thus provide a very efficient draft controlling mechanism for heating devices through which the draft checking air circuit can flow unhindered in the general direction of the chimney flue and without crowding, the door being balanced by a counter-weight and its upward movement resisted by a weight acting thereon with a leverage proportionate to the variation of 25 pressure against the door, the mechanism will control the furnace draft with great 30 efficiency and under all weather conditions.

I do not, of course, desire to be limited to the exact construction, arrangement and 35 operation shown and described, as modifications can no doubt be made which would still come within the scope of the invention. I claim as follows:

1. The combination with a chimney having a side opening, of draft regulator mechanism comprising a housing secured to said chimney to surround said side opening, said housing having an opening in its lower wall at an obtuse angle with the chimney side 40 whereby air may flow therethrough nearly in line with the upward passage of air through the chimney, a door pivoted to said housing adjacent the upper end of said housing opening to swing to and away from said opening, and adjustable weight mechanism for resisting the upward swing of said door in proportion to the pressure of inflowing air against the underside of the door.

45 2. The combination with a chimney having a side opening, of draft regulator mechanism comprising a housing secured to the chimney around its side opening and having an air entrance opening in its lower side in line with said side opening, a door hinged adjacent the outer end of said air entrance opening to swing in the path of air entering through said air entrance opening, a counter-weight for said door, and additional 50 weight controlled mechanism operating au-

tomatically to resist upward swing of the door in proportion to the varying upward pressure exerted by the air as the door assumes various angles with reference to the air entrance opening. 70

3. The combination with a chimney having an opening, of draft regulator mechanism comprising a housing secured to the chimney around said opening and having an air entrance opening, a shaft journaled 75 adjacent the upper end of said air entrance opening, a door secured at its upper edge to said shaft to open and close said air entrance opening and to swing in the path of air flowing through said air entrance opening into the chimney, a counter-weight for balancing the weight of said door, a pulley secured to said shaft, a cord secured at its upper end to said pulley and passing around the pulley periphery, a weight secured to the lower 80 end of said cord, said weight acting on said pulley and shaft to resist opening movement of said door, said pulley being eccentrically mounted on said shaft to cause the radius of engagement of said cord with said pulley to 85 decrease as the door is swung open by air pressure thereagainst and the resistance to said swing correspondingly decreased.

4. The combination with a chimney having a side opening, of draft regulator mechanism comprising a housing secured to said chimney over said side opening, a damper pivoted at its outer end in said housing and extending toward said chimney opening to swing vertically therein, the upper and lower walls of said housing forming abutments for said damper, said lower wall having an air inlet passageway which is closed when the damper is down, a counter weight for balancing said damper, a weight, and 90 adjustable leverage connection between said weight and damper for causing upward movement of said damper to be resisted in proportion to the pressure component 95 against the under side of said damper as said damper swings correspondingly decreased. 100

5. The combination with a chimney having a side opening, of a housing secured to said chimney over said opening, a damper pivoted at its outer end on said housing and extending toward said chimney opening to swing vertically therein, the lower wall of said housing having an air inlet opening, said inlet opening being closed by the damper in its lower position, a weight having 105 leverage connection with said damper intending to swing it downwardly toward closed position, and means for adjusting said leverage connection whereby to automatically decrease the downward effort on 110 said damper as the damper swings upwardly and the pressure of the air against its under side decreases.

6. The combination with a chimney having a side opening, of a draft regulator com- 115

prising a housing secured to said chimney over said opening, said housing having an air inlet opening, a damper pivoted in said housing for controlling said air inlet opening, a pulley eccentrically mounted with reference to the damper pivot and secured to the damper, a weight, a chain secured to said weight and to said pulley, and a plural-

ity of grooves on said pulley of different diameters for receiving said chain whereby 10 to adjust leverage connection between said weight and damper to thereby vary the resistance to the opening of said damper.

In witness whereof, I hereunto subscribe my name this 11th day of April, A. D., 1918. 15

T. R. STOLTENBERG.
